to American Can Company, New York, N. Y.,
a corporation of New Jersey

Application November 12, 1938, Serial No. 240,160

4 Claims. (Cl. 221—62)

The present invention relates to dredging cans and has particular reference to a self-closing sifter top powder or condiment can embodying a sliding closure member of an improved construction permitting handling of the can in one hand while moving and holding the sliding closure member in its open, sifter position.

In some respects the invention may be considered an improvement upon the structure disclosed in the R. W. Wilson Patent 2,123,643, issued by the United States Patent Office on July 12, 1938.

An object of the present invention is the provision of a dredging can which is equipped with a self-closing sliding closure member which remains in closed position until moved into an open position for dispensing, the opening and holding of the sliding member in its open dispensing position being easily effected by mere digital pressure applied directly to an end of the sliding closure.

Another object of the invention is the provision of a dredging can of the character described which consists of a few simple parts and the assembly of these parts may be easily made to condition the can for complete enclosure of the contents or for dispensing thereof.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a sifter top can embodying the present invention, this view illustrating the can held in one hand with the sliding closure member held in open or dredge dispensing position.

Fig. 2 is a perspective view of the sifter top can on a slightly larger scale without its sliding closure member;

Fig. 3 is a perspective view of the sliding closure member;

Fig. 4 is a top plan view of the can shown in Fig. 1 with parts of the slide member broken back; and

Fig. 5 is a transverse sectional view on an enlarged scale taken on the section line 5—5 in Fig. 4.

The present invention is concerned with a dredge top can for powders, condiments or the like having a spring held self-closing sliding closure member. The shape is unimportant and in the drawing such a can is shown as cylindrical in form and of somewhat conventional configura-

tion. The can comprises a can body 11 having a bottom end 12 secured thereto in a suitable seam as illustrated in Fig. 1.

Adjacent the top end of the body there is provided a reinforcing bead 13 (Figs. 2 and 5) which is pressed outwardly. Above the bead 13 the body wall extends up as a cylindrical neck 14 on which rests a top member. Such a top member consists of a cylindrical flange section 15, which engages the body neck in a tight frictional fit, and a breast 16 extending inwardly from the friction wall.

The upper edge of the body neck may be slightly ducked-in as at 17 and the lower edge of the top flange section 15 may be turned out in the beginning of a curl as at 18, these two features permitting easy joining of the top to the body. The part curl 18 engages and snugly fits the body bead 13 when the top and body are assembled and in a similar way the ducked-in edge 17 rests in the curved junction zone between the top parts 15, 16.

The breast 16 has an opening which is slightly off center for a purpose hereinafter explained and the edge of the metal of the breast surrounding the opening is flattened at the sides but its ends are rounded. A nozzle 21 is located in this opening. The nozzle also has flat sides and rounded ends and its edges are joined to the edges of the breast surrounding the central opening in a double seam connection 22. The nozzle 21 has a flat top wall 23 and a number of spaced sifter or dredge perforations 24 which are cut in this wall, these being located in rows.

The perforations 24 are adapted to be closed off or opened by the sliding closure member which is designated generally by the numeral 25 (Fig. 3). The closure slide 25 is cupped shaped having flat sides and rounded ends. It is formed with a flat top wall 26 and a peripheral skirt or flange 27 the lower edge of which is bent outwardly in a curl 28. Sifter or dredge perforations 29 cut through the top wall 26 of the slide have the same arrangement in number of rows and spacing as the perforations 24. These two sets of nozzle and slide openings are adapted for alignment as when the can functions in its sifter dispensing capacity.

The sliding closure member 25 is just wide enough for its flat side walls to slidably engage the flat side walls of the nozzle 21 when the closure member is in sliding position on the nozzle. In this position the flat slide wall 26 is in sliding contact with the flat nozzle wall 23 as best shown in Fig. 5. The member 25 is much longer than the nozzle 21 and the sliding movement possible.

between these parts is dependent on this difference in longitudinal dimension.

In one position one rounded end of the slide member is against the adjacent rounded end of the nozzle but the opposite rounded slide end is spaced from its adjacent rounded nozzle end. This is best shown in Fig. 4.

Provision is made for holding the closure slide wall 26 down tightly against the nozzle wall 23 at all times, that is, irrespective of the relative longitudinal positions of slide and nozzle. An outwardly pressed bead 31 (Figs. 3 and 5) is formed in each straight side of the flange wall 21 of the closure member and two outwardly pressed projections 32 (see also Fig. 2), formed in each straight side wall of the nozzle 21, extend into each bead. This permits free sliding of the closure member 25 but always holds the same down on the nozzle 21.

It will be recalled that mention was made of the nozzle 21 being off center of the axis of the can. When the slide closure 25 is centrally disposed on the can (this being the position of the parts in Fig. 4) the slide perforations 29 are not in register with the nozzle perforations 24. The can is therefore closed and this is the normal position of the sifter parts. This normal position is maintained by means of a spring element which will next be considered.

By reason of the off center position of the nozzle 21 a space is left between the end wall of the nozzle (at the right in Fig. 4) and the right end wall of the slide. It is in this space that the spring element referred to is disposed. Both of the end walls of the slide member flange 27 along a longitudinal axis, is pressed outwardly in a protuberance 35 (Figs. 3 and 4). One of these protuberances provides a pocket for a coil spring 36 (see also Fig. 3) and two ends 37 of the spring extend toward and abut the adjacent end wall of the nozzle.

Only one protuberance 35 is used in each can but having two, one on each side, gives symmetry of design and also provides for ease of assembly. In such assembly, it is merely necessary to place the spring 36 on the top of the breast 16, as illustrated in Fig. 2, and then the slide member 25 may be brought down over the nozzle. Dot and dash lines connecting Figures 2 and 3 indicate this relationship between slide and nozzle. The coil body of the spring is thus easily seated in whichever protuberance 35 happens to be on that side and the legs 37 of the spring assume the position shown in Fig. 4 the spring then being under slight tension.

Either the fully formed projections 32 may be sprung inwardly by the slide skirt 27 during this assembly just enough to permit passage of the slide member into sliding position, or the projections 32 may be subsequently formed by being pressed out after the parts are in place. If the projections are fully formed, the spring in the metal of the nozzle and also in the slide is such as to cause the projections to snap out into holding position within the bead 31 when the parts are fully assembled.

When the completely formed, filled and closed can is to be used as a dredging or sifter can in the dispensing of its contents, it need only be grasped in one hand, partially inverted as shown in Fig. 1 and at the same time the thumb is pressed in against that protuberance 35 in which the spring 36 is seated.

This digital pressure on the slide member moves the latter until its perforations 29 align

with the perforations 24 of the nozzle the spring legs 37 at such time spreading apart as their ends slide along the end wall of the nozzle. Since the spring 36 at such time is under its greatest tension it is necessary to hold the slide in open position while the dispensing of the can contents is being effected. As soon as released the spring returns the slide member to closed position. This is the self closing feature which has been previously mentioned and which is very valuable in the packaging of many types of powders or similar contents.

The legs 37 of the spring 36 can only spread so far and there is therefore only possible a definite movement of the slide before the end wall of the skirt portion 27 is stopped by the nozzle wall. This is constructed to be the full open position of the can which thus has an exact slide movement between its closed position and its open position.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A self-closing dredge top can closure comprising a nozzle section having vertical walls and a flat top, the latter being cut through with sifter perforations, a slide member located in sliding position on said nozzle section, said slide member having vertical walls and a flat top which engages the flat top of said nozzle, said sliding member flat top having sifter perforations which normally are out of register with said nozzle perforations, and a spring element interposed between said nozzle and slide and yieldably maintaining the closure in its closed condition, said slide member being movable under digital pressure applied to a said vertical slide wall and against the action of said spring element to bring said nozzle and slide perforations into register to provide for sifter dispensing of the contents of the can.

2. A self-closing dredge top can closure comprising a nozzle section having vertical walls and a flat top, the latter being cut through with sifter perforations, a slide member located in sliding position on said nozzle section, said slide member having vertical walls and a flat top, the latter engaging the flat top of said nozzle, beaded sliding connections formed in the cooperating vertical walls of said slide and nozzle, said slide flat top having sifter perforations cut therethrough which normally are in can closing position and out of register with said nozzle perforations, and a spring element interposed between adjacent vertical walls of said nozzle and slide and yieldably maintaining the closure in its normal closed condition, said slide member being movable under digital pressure applied to a said vertical slide wall and against the action of said spring element to bring said nozzle and slide perforations into register to provide for sifter dispensing of the contents of the can.

3. A self-closing dredge top can closure having straight and curved vertical walls and a flat top, the latter being cut through with sifter perforations, a slide member located in sliding position on said nozzle section, said slide member having straight and curved vertical walls and a flat top,

- the straight walls of said slide member slidably engaged on the outside of the straight walls of said nozzle section and the flat tops of said slide and nozzle also slidably engaging each other being so held by beaded connections formed in said straight walls, said slide flat top having sifter perforations cut therethrough which are normally out of register with the said nozzle perforations and in can closing position, and a spring 5 element interposed between the curved walls of said nozzle and slide and yieldably maintaining the closure in its closed condition, said slide member being movable under digital pressure applied to a said curved vertical slide wall, such pressure being yieldably resisted by the spring pressure of 10 said spring element, said nozzle and slide perforations being in registration and conditioning the can for sifter dispensing of the contents thereof when so moved.
- 15 4. A self-closing dredge top can closure having straight and curved vertical walls and a flat top, the latter being cut through with a plurality of rows of sifter perforations, a slide member located in sliding position on said nozzle section,
- 10 said slide member having straight and curved vertical walls and a flat top, the straight walls of said slide member slidably engaging on the outside of the straight walls of said nozzle section and the flat tops of said slide and nozzle also 15 slidably engaging each other, a spring pocket formed on the inside of a curved vertical wall of said slide, said flat top of said sliding member having a plurality of rows of sifter perforations which are normally out of register with the said 20 nozzle perforations thus normally closing the can, and a coil spring seated in said spring pocket of the slide having legs which engage an adjacent curved vertical wall of said nozzle and yieldably maintaining the can in its closed condition, said 25 slide member being movable under digital pressure applied to said curved vertical slide wall adjacent said spring pocket for aligning the perforations of said slide and nozzle and conditioning the can for sifter dispensing of the contents thereof when said slide member is moved the maximum distance permitted by said yielding spring.
